UNITED STATES PATENT OFFICE.

JOSEPH ZUBATY, OF FLINT, MICHIGAN, ASSIGNOR TO A C SPARK PLUG COMPANY, OF FLINT, MICHIGAN, A COMPANY OF MICHIGAN.

CLOCK CONSTRUCTION.

Application filed January 22, 1926. Serial No. 83,027.

This invention relates to a clock for an automobile instrument board.

In placing a clock upon an instrument board a difficulty has arisen in that the location of the clock movement in close proximity to the board positions the winding stem so closely to the board as to be difficult of manipulation.

It is an object of this invention to conveniently locate the winding stem away from the instrument board.

A further object is to arrange for the use of a thin clock movement and a spaced dial the arrangement being intended for the location of the dial adjacent the instrument board while the clock movement with its winding stem is considerably removed from the board. A further object is to get a clock assembly of variable depth, and one which makes use of but very few special parts to secure the variability; and another advantage to be attained is the possibility of putting any shape or size of bezel projecting through the instrument board on the same clock assembly whereby the final appearance of the clock is determined.

With these and other objects in view, the invention has been embodied in certain structures as herein shown and described in the accompanying drawings.

In the drawing:

Figure 1 is a front elevation looking toward the instrument board from within the car. Figure 2 is a vertical section on line 2—2. Figure 1. Figure 3 is a horizontal section on line 3—3 in Figure 1. Figure 4 is a section through the spindle.

Referring to the drawing, reference numeral 1 is used to represent the instrument board of a car. Numeral 2 shows a base member, in a recess 3 of which is placed a comparatively thin clock movement 4. This clock movement is held in position by screws 5. Projecting from the base is an apertured lug 6 carrying an extended sleeve 7. Through this sleeve projects a winding stem 8 having at its outer end a handle 9. Different from the usual clock construction the dial 10 is spaced from the clock movement by means of a plurality of sleeves 11. Passing through the dial and sleeves 11 and threaded into base 2 are fastening screws 12. For the purpose of driving the hands of the clock, 13 two tubular driving spindles 14 and 15 are made use of. These spindles en-

gage the usual hand driving means of the clock and extend to a point just beneath the spaced dial. Suitable means for moving the hands is provided by a spindle 16 and sleeve 17 passing through the dial and making a connection with the driven members 14 and 15.

To complete the clock case a cylindrical casing member 18 is secured to the base 2. This casing member extends to a point somewhat beyond the dial where it is provided with an annular outwardly projecting flange 19. A plate 20, circular in shape, is depressed between its outer portion and its central portion, and the central portion is cut out as at 21 to form with the dial a clock face of appropriate size and shape. It will be seen that the opening is out of the plane of the major part of the plate and the connecting portion is formed as a ledge 22 to engage the glass 23. Cooperating with the plate 20 is a plate 24. This plate 24 has its central portion cut out and is formed with a bead 25. This bead engages the glass around the opening, the opening corresponding in shape and size with the opening in plate 20. Plate 24 is of greater extent than the plate 20 and its outer wall is bent over to form an annular pocket. Within this annular pocket are the flange of the member 18 and the outer portion of the plate 20. An annular spacing member 26 may also be made use of between the flange of casing member 18 and plate 20. This member 26 is preferably a gasket to seal the assembly from dust.

For securing the clock case to the instrument board, clamps are made use of comprising threaded bolts 27 and U-shaped members 28. One of the arms of the U-shaped member engages the instrument board and the other engages the turned over edge of plate 24 as will be readily understood from examination of the drawing.

By the mechanism described above it is possible to use a thin clock movement in a relatively deep case. The clock movement being at the bottom of the case and its winding stem projecting therefrom considerably removed from the instrument board. In so positioning the clock movement the disadvantages of remoteness of the dial is overcome by spacing the dial from the movement and making use of relatively long driving spindles for the hands. The means for se-

curing the clock case on the board is such as to obtain the desired position of the dial and cooperating therewith is the novel means for holding the clock glass into position.

- 5 By the use of the parts, as described, assemblies of varying depths are provided for use upon different instrument boards. But few special parts are needed to accomplish this purpose, i. e., the casing 18, spacing members 11, screw 12 and sleeves 14 and 15. These parts are all simple and cheap to manufacture.

10 The essential parts of the clock, such as the clock movement 4, dial 10 and hands 13, would be the same in each case. In this way it would be possible to have one model of clock manufactured in several depths, the main parts being identically the same, which is important from the point of view of 15 accessibility of the re-winding stem and also for interferences which may occasionally occur when the clock is combined with several other instruments in one unit or panel, and would therefore be made shallower or 20 deeper according to circumstances.

25 A further advantage of this design, which will be readily understood from the foregoing description, is a possibility of putting any shape or size of bezel projecting through

the instrument board on the same clock assembly. This is made possible by using a plate 24, having a bead 25, the shape of which controls the final appearance of the clock from the outside. It is obvious that very many different sizes and shapes of bead 25 can be had and still the circular plate 24 will fit the same flange 19 on the casing 18.

30 It will be, also, readily seen that these features make this type of construction an important improvement from the manufacturing standpoint.

35 Modifications of the specific structure shown and described above are possible and are within the contemplation of the inventor.

40 I claim:

45 In combination, a clock movement having a frame, a removable coaxial casing in extension of the frame, a dial in the end of the casing remote from the frame, means for fixing the dial to the frame and casing, a removable extension shaft connecting the movement with the dial hands, and means for securing the casing to an instrument board.

50 In testimony whereof I affix my signature.

JOSEPH ZUBATY.
